LEVELING MEANS FOR A LAP TRAY

Albert E. Malmer, Blue Island, Ill.

Application October 26, 1956, Serial No. 618,542

8 Claims. (Cl. 311—25)

My invention relates to trays in which food or beverages are served informally, this being done by depositing the tray on the guest's lap. While one often manages to keep a tray so deposited level or nearly so, doing this is frequently difficult, and there is always the danger that the articles on the tray will slide forward or tip over. Various devices have been developed to adjust the tray to a horizontal position, but such of these devices as have come to my attention are either complicated or require frequent attention. It is therefore one object of the present invention to provide an adjusting device which may be manipulated readily to set the tray in horizontal position in relation to the latter.

A further object is to provide a device of this kind which is adjustable with ease to different angles of the lap, whereby to render the tray suitable for any person.

An additional object is to design the device in a manner to maintain its position at any point of adjustment and keep the tray steady.

Another object is to construct the device with means to adapt it readily to trays of conventional size.

An important object is to employ a minimum number of parts in the assembly of the device.

With the above objects in view, a better understanding of the invention may be had by reference to the accompanying drawings, in which—

Fig. 1 is a front elevation of a conventional serving tray;

Fig. 2 is a section on the line 2—2 of Fig. 1, showing the manner in which the tray as equipped with the novel device is suspended on a wall;

Fig. 3 is a rear view of the tray, showing the device attached to it;

Fig. 4 is a view from the right-hand side of Fig. 1, and similar to Fig. 2;

Fig. 5 is an elevation showing the tray and the device adjusted to a gradually sloping lap;

Fig. 6 is a similar view, showing the assembly adjusted to a steeper lap;

Fig. 7 is a section on the line 7—7 of Fig. 1, showing the tray in horizontal position and the device set in readiness for use;

Fig. 8 is a section in the right-hand portion of Fig. 7, illustrating a clamping device;

Fig. 9 is a perspective view of one of the tray supports in the device, showing a bearing for the support;

Fig. 10 is an end view of the support and the bearing;

Figs. 11 and 12 are, respectively, sections on the lines 11—11 and 12—12 of Fig. 10;

Fig. 13 is a view similar to Fig. 3, showing a tray made with the adjusting device;

Figs. 14 and 15 are, respectively, sections on the lines 14—14 and 15—15 of Fig. 13;

Fig. 16 is a side elevation of a modified supporting member; and

Fig. 17 is a section on the line 17—17 of Fig. 16.

In accordance with the foregoing, specific reference

2

to the drawings indicates a typical serving tray at 25. Trays of this type usually come in two or three sizes, and it is intended that the preferred form of the invention be made as an attachment and in sizes corresponding to those of the trays.

Primarily, the attachment is in the form of a frame 27 of flat metal stock, and bent with end pieces 28. These are attached by means of screws 30 to a wooden rail 32, such rail completing the frame. The upper side 10 of the rail receives a pair of rubber buttons 33.

The frame 27 is designed to be attached to any serving tray of corresponding size by means of a wire clamp 35. As shown in Fig. 3, the frame 27 is applied to the bottom of the tray from underneath; and the wire clamp 35 extends longitudinally within the frame to pass through holes 37 in the end pieces 28 and terminate with a pair of clips 38. These are designed to grip the rim of the tray, as shown in Fig. 7; and the lower portions 39 of the clips are rounded to form finger pieces for the handling of the clips. The wire clamp 35 includes a coil spring 40. Thus, by drawing the clips apart, they can be engaged with the rim of the tray. With the frame 27 applied as shown in Figs. 3 and 7, the wire clamp keeps the frame in firm engagement with the tray, so that the latter and the attachment may be handled in one piece.

For the purpose of the present invention, it is necessary that the frame 27 be pivotable in relation to the tray, and the buttons 33 abutting the bottom of the tray 25 form the pivots on which the attachment may be swung to the position indicated in Fig. 5. Here, the attachment is shown as having followed the inclination of a person's lap 45, while the tray remains in a horizontal position. This position of the tray may be maintained by rotating a pair of blocks 47 situated along the end pieces 28 from the horizontal position shown in Fig. 3 to the substantially vertical position shown in Fig. 5. Thus, the blocks now will form supporting elements for the frontal portion of the tray upon the lap 45; and the blocks are grooved in the bottom, as indicated at 48, to afford a finger grip when adjusting the block. It is noted that the top of each block is slightly beveled to accommodate itself to the bottom of the tray 25.

It will be understood that the purpose of having the blocks 47 in the horizontal position initially is to position them flatly or against the bottom of the tray for compact wrapping or shipping. Each block 47 is made with a bore 50 for the passage of the corresponding end piece 28. While the aforesaid rotation of the block is feasible by mounting the same as stated, a bearing for it is provided to counteract possible angular motion. Thus, the bearing is formed by two strips 52 of sheet material placed on opposite sides of the end piece 28 and passing through the block 47, as shown in Fig. 3. The strips are of right angle form and have rounded corners in engagement with the wall of the bore 50. In addition, the strips 52 are recessed in the said corners, as indicated at 53, so that the outer portions of the strips overlap the ends of the blocks 47 and prevent the strips from sliding out of the blocks.

With the block situated as just described, it may, however, be slid as assembled with the strips 52 along the end piece 28. Thus, with the block assemblies located at a forward point, as in Fig. 5, the tray 25 is maintained in a horizontal position where the person's lap has a gradual slope. However, where the inclination of the lap is more pronounced, as in Fig. 6, it is only necessary to slide the blocks 47 rearwardly to take up the angle to a degree maintaining the tray in a horizontal position.

It may be of advantage to manufacture the tray in-

tegrally with the adjusting device as a modification, in which event the rail 32 would be permanently attached to the tray, and the frame 27 would pivot on screws 60 driven from the end pieces 28 into the ends of the rail, as indicated in Fig. 13. While the spring clamp 35-40 in the first described form of the invention served to draw the frame 27 and the blocks 47 to the tray, the modification of Figs. 13 to 15 employs angle springs 62 in the corners between the end pieces 28 and the rail 32, these serving to urge the frame toward the tray.

Figs. 16 and 17 show a modification of the blocks 47 where it is desired that the frame 27 be made of round rod stock instead of flat stock. In such case, it is preferable that the block be provided with a friction element to maintain it at any position to which it is set, and a simple form of such element is a spring-backed ball 65 lodged in a cavity 66 made longitudinally of the block. The frame rod 68 passes through a crossbore 70 made in the block, and it is understood that the ball 65 will have sufficient frictional contact with the surface of the rod to maintain the block as set.

It will now be apparent that the novel adjusting device, in either of its applications, is a compact under-mounting for serving trays to adapt them readily to the inclination of the user's lap. The adjustment of the tray does not involve the use of screws, springs or other delicate mechanisms; and positive means are employed to secure such adjustment in the form of the slidable blocks 47. These are located at the sides of the tray for handy reach with the fingers. Finally, the adjusting device is a compact accessory involving few and simple parts, and therefore of a nature to be produced at relatively low cost.

While I have described the invention and its modifications along specific lines, various minor changes or refinements may be made therein without departing from its principle, and I reserve the right to employ all such changes and refinements as may come within the scope and spirit of the appended claims.

I claim:

1. A lap tray leveling device adapted to be secured to the underside of a tray comprising a base member having at least two leg portions, means pivotally securing said legs to said tray, and means slidably engaging said legs and movable the length thereof to position said base at varying angles in its pivotal movement whereby said tray is maintained in a horizontal position.

2. A lap tray leveling device adapted to be secured to the underside of a tray comprising a base member having at least two leg portions, means pivotally securing said legs to said tray, and a pair of elongated blocks having a bore therethrough slidably engaging said legs and movable the length thereof to position said base at varying angles in its pivotal movement whereby said tray is maintained in a horizontal position.

3. A lap tray leveling device adapted to be secured to the underside of a tray comprising a base member having at least two leg portions, means pivotally securing said legs to said tray, spring means urging said legs in contact with said tray, and a pair of elongated blocks having a bore therethrough slidably engaging said legs and movable the length thereof to position said base at varying angles in its pivotal movement whereby said tray is maintained in a horizontal position.

4. A lap tray leveling device adapted to be secured to the underside of a tray comprising a U-shaped base member having legs and a bight portion, means pivotal-

ly securing said legs at their free ends to said tray, spring means urging said legs in contact with said tray, and a pair of elongated blocks having a bore therethrough slidably engaging said legs and movable the length thereof to position said base at varying angles in its pivotal movement whereby said tray is maintained in a horizontal position.

5. A lap tray leveling device adapted to be detachably secured to the underside of trays of varying sizes comprising a U-shaped base member having legs and a bight portion, spring means urging said legs in contact with said tray and terminating in tray gripping brackets, and means slidably engaging said legs and movable the length thereof whereby said legs and bight portion are capable of being raised and lowered relative to said tray to maintain said tray in a horizontal position.

10 6. A lap tray leveling device adapted to be detachably secured to the underside of trays of varying sizes comprising a U-shaped base member having legs and a bight portion, spring means urging said legs in contact with said tray and terminating in tray gripping brackets,

15 and a pair of elongated blocks having a bore therethrough slidably engaging said legs and movable the length thereof whereby said legs and bight portion are capable of being raised and lowered relative to said tray to maintain said tray in a horizontal position.

20 7. A lap tray leveling device adapted to be detachably secured to the underside of trays of varying sizes comprising a U-shaped base member having legs and a bight portion, spring means urging said legs in contact with said tray and terminating in tray gripping brackets,

25 and a pair of elongated blocks having a cylindrical bore therethrough slidably engaging said legs and movable the length thereof whereby said legs and bight portion are capable of being raised and lowered relative to said tray to maintain said tray in a horizontal position, said blocks being rotatable on said legs to horizontal position seating the tray compactly on the frame, and guides in said bores to maintain said blocks in uniform position on said legs.

30 8. A lap tray leveling device adapted to be detachably secured to the underside of trays of varying sizes comprising a U-shaped base member of cylindrical stock having legs and a bight portion, spring means urging said legs in contact with said tray and terminating in tray gripping brackets,

35 and a pair of elongated blocks having a cylindrical bore therethrough slidably engaging said legs and movable the length thereof whereby said legs and bight portion are capable of being raised and lowered relative to said tray to maintain said tray in a horizontal position, said blocks being rotatable on said legs to horizontal position seating the tray compactly on the frame, and said blocks having leg gripping means therein comprising a ball tensioned against said leg by a spring whereby said blocks are maintained in uniform position on said legs.
